UNITED STATES PATENT OFFICE.

AMON T. NOE, OF PARNASSUS, PENNSYLVANIA, ASSIGNOR TO ELECTRIC RENOVATOR MANUFACTURING COMPANY, A CORPORATION OF PENNSYLVANIA.

DUST-COLLECTOR.

No. 918,897.

Specification of Letters Patent. Patented April 20, 1909.

Application filed March 28, 1908. Serial No. 423,903.

To all whom it may concern:

Be it known that I, AMON T. NOE, a citizen of the United States, residing at Parnassus, in the county of Westmoreland and State of 5 Pennsylvania, have invented certain new and useful Improvements in Dust-Collectors, of which the following is a specification.

My invention relates to dust collectors, and more particularly to devices of this 10 character designed for use in connection with pneumatic renovating apparatus, such as is commonly employed in house cleaning.

The present invention relates to certain improvements in the type of dust collector 15 illustrated in my prior application Serial Number 393,936, filed September 21st, 1907.

The primary object of the invention is to provide a dust collector which shall be so constructed as to effectively prevent the 20 escape of dust therefrom but from which accumulations of dust may be quickly and readily removed.

A further object of the invention is to provide improved means for delivering the dust 25 laden air into the collector.

With the above and other objects in view my invention consists in the construction and arrangement hereinafter described and illustrated in the accompanying drawings in 30 which—

Figure 1 is a central longitudinal section through my improved dust collector, complete. Fig. 2 is a perspective view of one of the supporting frames hereinafter described. 35 Fig. 3 is a side elevation of the removable end member of the dust collector casing. Fig. 4 is a central longitudinal section through one of the parts hereinafter described.

40 Referring to the drawings in detail my improved dust collector comprises a casing 1, preferably cylindrical, the walls of which are foraminous and which may consist either of wire gauze or as shown of perforated sheet metal. The upper end of the casing 1 is closed by means of an end plate 2 having a central opening provided around its edge with a depending annular flange 3. The end plate 2 also carries a number of perforated 45 50 lugs 4 around its edge.

Into the lower end of the casing is fitted a ring 5, provided with a plurality of lugs 6, corresponding with the lugs 4 on the upper end plate. Rods 7 pass through pairs of cor-

responding lugs and are screw threaded at 55 one end to receive thumb nuts 8 by means of which the two ends of the casing are secured together.

The end plate 2 is provided with a series of internally projecting, annular, concentric 60 ribs 9, the purpose of which will be herein-after described. Secured to the ring 5 and projecting upwardly and inwardly therefrom are a plurality of arms 12 connected at their upper end by a smaller ring 11. The 65 arms 12 are provided on their upper surface with a series of notches or steps 13, the purpose of which will now be described. Resting in these notches are a plurality of concentrically arranged supporting frames one 70 of which is clearly shown in Fig. 2. Each of these frames comprises upper and lower rings 10 connected by a plurality of brace rods 14. As clearly shown in the drawings these frames are of progressively decreasing 75 diameter and are concentrically arranged one within the other in stepped relation, the inner frame being the shortest, but the top of all of the frames lying substantially in the same plane and some distance below the end 80 plate 2.

Alternating with the frames above described is a second set or series of similar frames comprising upper and lower rings 15 connected by brace rods 15^a. The upper 85 rings 15 are held in position by means of the annular ribs 9 on the end plate 2.

Secured to one end of the casing as at 17 is one end of a continuous web or fabric 16, which fabric is preferably of closely woven 90 though porous material, and is looped back and forth around the ends of the above described alternating frames. As will be seen from Fig. 1 this web or fabric passes over the tops of the rings 10 and under the bottom 95 edges of the rings 15 thereby forming a support for the latter and holding them up in such position that their upper ends abut against the top plate 2. The inner end of the fabric is secured, as at 18, to the flange 3 depending from the top plate, and provided with a groove to accommodate a suitable tie wire or the like. It will therefore be seen that the two sets of frames cause the tubular web or fabric to assume such shape as to form 100 105 a series of annular concentric chambers of tapering form, having porous walls some of which, as 23, open upward, while the others,

as 24, open downward. It will be observed however that the chambers 23 which open upward have no communication with the other chambers or with the delivery pipe and 5 do not serve to collect the dust. It will be noted that none of these frames is attached in any way to the casing, but are separate and independent elements. The lower set of frames rest in the notches of the arms 12, 10 while the upper set rest loosely in the loops of the fabric, and are merely suspended thereby. The result of the employment of these "floating" frames is that by removing the lower end ring of the casing, the entire 15 dust collecting structure can be readily removed and disconnected, whenever it is desired to clean or renew the same.

The lower end of the casing 1 is closed by means of the removable bowl-shaped bottom 20 19 fitted with locking cams 20 coöoperating with projections 20^a formed on the ring 5. Projecting upwardly from the center of this bottom 19, and preferably formed integral therewith is a post 21 which when the bottom 25 is in its position in the casing projects well up into the innermost chamber of the series. At its upper end this post carries a conical spreader 22 or baffle plate hereinafter referred to. Also secured to the flange 3 and depending below the same is an annular flap 25 formed of some flexible material, which flap aids in preventing the leakage of dust past the flange 3. Fitted within the opening which the flange 3 surrounds is one end of a 30 conduit 26, the other end of which is adapted to be connected with the discharge from any suitable fan or pump and thus serves to deliver dust laden air into the casing. It will be seen therefore that the dust laden air entering the innermost chamber through the conduit 26 impinges against the spreader 22 at the lower end of this chamber and is thereby deflected and caused to spread through the bottom part of the casing from 35 which it diffuses upward into the annular chambers 24, the dust being retained by the walls of fabric and the air filtering through the same and escaping through the outer walls of the casing. It is to be noted that the 40 dust is collected in the chambers which open downwardly the other chambers being entirely closed. This construction results in the dust all accumulating on one side of the fabric and in one end of the dust collector. 45 It will, therefore, be apparent that by gently tapping or jarring the casing, all of the entrapped dust will fall into the bowl-shaped bottom 19 which may then be removed and emptied.

50 60 The end plate 2 is not rigidly secured to the casing 1 but can slide freely therein, and hence, by screwing up the thumb nuts 8 and thus drawing in the end plate the lower ends of the partitions 15 will be forced against the 65 loops of the fabric in which they rest and this

serves to put and maintain the fabric under tension.

It will thus be seen that I have provided a dust collector which is simple to construct, and which may be very easily and quickly cleaned, and it is thought the numerous advantages thereof will be readily appreciated by those skilled in the art.

What I claim is:—

1. A dust collector comprising an outer 75 cylindrical casing having porous walls, a plurality of separate and independent skeleton frames concentrically disposed therein, each frame comprising a pair of end rings spaced apart and connected by brace rods, a filtering 80 sack stretched alternately over the upper rings and under the lower rings of said frames to provide a series of annular dust collecting chambers all of which open toward the lower end of the casing, a removable closure for said 85 lower end, and a delivery conduit for dust-laden air leading through the upper end of the casing and discharging centrally thereof.

2. A dust collector comprising a series 90 of annular, concentric chambers, means for delivering dust-laden air into one end of the innermost chamber, and a conical spreader located at the other end of said chamber, against which the current of incoming air impinges.

3. A dust collector comprising an outer foraminous casing, a plurality of frames nested therein one within the other, a filtering sack stretched over said frames and co-operating therewith to form a series of annular dust collecting chambers all of which open toward the lower end of the casing, a conduit for discharging dust-laden air through the upper end of the casing, and a deflector within the casing opposite and in line with the 105 said conduit.

4. A dust collector comprising an outer foraminous casing, a plurality of frames nested therein one within the other, a filtering sack stretched over said frames and co-operating therewith to provide a series of concentric annular dust collecting chambers all of which open toward the lower end of the casing, a removable closure for said end, a deflector carried by said closure and disposed 110 within the casing, and an inlet for dust-laden air discharging through the opposite end of the casing in line with said deflector.

5. A dust collector comprising an outer foraminous casing having a closure at the upper end provided with a central inlet opening for dust-laden air, a removable closure for the opposite end of the casing provided with an upwardly projecting spout carrying a conical deflector at its end situated in line 125 with the said inlet opening, frames nested one within the other in said casing and a filtering sack looped back and forth over said frames to provide a series of annular concentric dust collecting chambers, all of which 130

open toward that end of the casing carrying the removable closure.

6. A dust collector comprising an outer foraminous casing, concentrically arranged frames therein nested one within the other, a filtering sack looped about said frames and co-operating therewith to provide a series of concentric annular dust collecting chambers all of which open toward the lower end of the 10 casing, a removable closure for said end, a conical deflector located centrally within the casing, and an inlet conduit for dust-laden air discharging through the opposite end of the casing in line with the said deflector.

15 7. A dust collector comprising an outer foraminous casing having an upper end plate formed with a central intake opening for dust-laden air, provided with an internally projecting flange, frames nested one 20 within the other in said casing, a tubular filtering fabric looped back and forth over said frames to provide a series of concentric annular dust collecting chambers, all of which open toward the lower end of the casing, one 25 end of said tubular fabric enveloping and secured to the said internally projecting flange

on the upper end plate, and a removable end-plate for the lower end of the casing.

8. A dust collector comprising an outer foraminous casing having an end plate 2 formed with a central intake opening for dust laden air and provided with an internally projecting flange, frames nested one within the other in said casing, a tubular filtering sack looped back and forth over said frames 35 to provide a series of annular concentric dust collecting chambers, all of which open toward the lower end of the casing, one end of said tubular fabric enveloping and secured to the said internally projecting flange on the end plate, a removable end-plate for the lower end of the casing provided with an inwardly 40 projecting spout, and a conical deflector on the end of said spout facing the said intake opening.

In testimony whereof I have affixed my signature in presence of two witnesses.
